(57) CLAIM

The ornamental design for a car charger, as shown and described.

DESCRIPTION

FIG. 1 is a perspective view of a car charger showing our new design;

FIG. 2 is a Front side view thereof, the rear view being a mirror image thereof;

FIG. 3 is a Right side view thereof, the Left side view being a mirror image thereof;

FIG. 4 is a top view of the car charger;

FIG. 5 is a bottom view of the car charger; and,

FIG. 6 is a Front side view thereof, shown in an environment of use.

The broken lines in the figures represent portions of the article which form no part of the claim.

1 Claim, 2 Drawing Sheets
